UNITED STATES PATENT OFFICE.

ARTHUR W. SNOW, OF NEWARK, NEW JERSEY, ASSIGNOR TO THE PRYOR NOVELTY COMPANY, OF NEWARK, NEW JERSEY.

DESIGN FOR A BACK FOR HAND-MIRRORS OR SIMILAR ARTICLES.

SPECIFICATION forming part of Design No. 36,931, dated May 24, 1904.

Application filed April 30, 1904. Serial No. 205,826. Term of patent 3½ years.

To all whom it may concern:

Be it known that I, ARTHUR W. SNOW, a citizen of the United States, residing at Newark, in the county of Essex and State of New Jersey, have invented a new, original, and ornamental Design for Backs for Hand-Mirrors or Similar Articles, as shown in the accompanying drawing.

In the accompanying drawing the single figure shows in front elevation a back for hand-mirrors and similar articles of my new and ornamental design.

What I claim as new is—

The ornamental design for a hand-mirror back and similar articles as shown.

ARTHUR W. SNOW.
